ABSTRACT OF THE DISCLOSURE

A shovel loader is provided having a transportable substructure, a shovel movable on said substructure from a low digging and loading position to an elevated discharge position, an operator manipulated means on the substructure for arresting and holding said shovel in an intermediate position between said low digging and said elevated discharge position.

This invention relates to improvements in shovel loaders and one object of the invention is to provide shovel loaders of the type in which a shovel is movable on a substructure from a low digging and loading position in front or somewhat sideways of the loader to a raised discharge position in which the shovel discharges its contents into a hopper, a mine car or some other receiver or onto a conveyor for the material to be handled. It is often desirable to be able to operate such shovel loaders in inclined shafts or tunnels or similar underground passages. The shovel in machines of this type is usually operated by a separate shovel operating motor whereas motor or motors are provided for driving traction means such as wheels or bands. In many cases such a loader must move a short distance on an incline from a pile of material where it is digging towards a receptacle or mine car or the like in which the shovel is going to be discharged and during this movement the shovel has to be carried in a position between digging position and discharge position. This is difficult for the operator and consumes unnecessary amounts of air or other operating energy. When a loader constructed in this way reaches the material receiver or mine car behind the loader the operator can fulfil the throw and throw the contents of the shovel into the mine car or receptacle or the like, and then return to the pile of material.

In the drawings one embodiment of a loader according to the invention is illustrated by way of example but the invention may naturally be modified in several different ways. In the drawings FIG. 1a and 1b illustrate a shovel loader working in an inclined mine shaft. FIG. 1a shows the loader in digging position and FIG. 1b shows the loader in position ready to throw the material contents of the shovel into a mine car. FIG. 2 is a side view and partial longitudinal section of a shovel loader of the type illustrated in FIGS. 1a and b on a larger scale. FIG. 3 is a side view and partial section illustrating a catching means in the form of a pressure fluid operated hook member and FIG. 4 is a section on line IV—IV in FIG. 3. FIG. 5 is a front end view and partial transverse section and FIG. 6 a side view of the operating member and control valve for the catching means.

The loader illustrated in FIGS. 1a and b in FIG. 2 consists of a substructure 1 carried by four traction wheels 2 operated by a not illustrated traction motor. The loader is provided with a shovel 3 which is carried by an arm structure which in the present case consists of two rocker arms 4 which by means of rocker members 5 may roll on guide rails 33 on the substructure from a low digging or filling position, as illustrated in FIG. 1a full lines, to a raised

2

discharge position as illustrated in chain dotted lines in FIG. 1b. This type of loader is well known in the mining art and the invention is also applicable to other types of similar loaders, for instance to the type of loaders in which the shovel arms are pivotally mounted on a transverse shaft in the front portion of the substructure 1. Furthermore, many loaders of the above type have a substructure divided in an upper and a lower part, the upper part being capable of swivelling on a vertical axis relative to the lower part to enable the shovel to dig in positions swung towards the sides of the longitudinal center line of the loader.

The illustrated loader is of the pneumatically operated type, but the invention is also applicable to electrically driven loaders. The illustrated loader is provided with a shovel operating motor 6 which drives chain reel 7 for a shovel operating chain 8 carried over a roller 9 mounted at the discharge end of the loader. The chain 8 is connected to a transverse bar 10 secured to the shovel arm structure 4 by side members 11. A second transverse bar 12 is secured to and extends between the rocker arms 4 and forms a catch engaging member for the shovel arm structure. A heavy hook member 13 is journaled on a transverse shaft 14 mounted on brackets 15 on the substructure 1. The hook member 13 is provided with a downwardly directed arm 16 which is pivotally connected to a link 17 which is connected with a piston rod 18 of a membrane piston provided in a conventional membrane piston housing 19. The housing 19 has a throat 35 which is screw threaded as at 20 and may be locked by a screw 21 provided in a member 34 by engaging the screw thread 20 in order to lock the housing throat 35 in a position in which the hook member 13 cooperates with the rocker arm structure and particularly the transverse bar 12 in a proper way. The member 34 swings on pivots 38 fitted in the brackets 15.

The membrane piston housing 19 is connected through a conduit 36 to a control valve housing 22 at 23. The control valve housing 22 contains a shovelling control valve (not illustrated) and an auxiliary valve 24 for the membrane housing 19 which may be operated by a lever 25. Operation of the lever in the direction of the arrows 26" and 26' operates the motor 6 for raising or dumping of the shovel in conventional manner. The lever 25 may also be operated in the direction of the arrow 27 and upon such operation the lever 25 swings on pivots 37 and operates the valve 24 to a position in which air is admitted to housing 19 and the membrane piston in the housing moves the rod 18 against spring pressure so that the hook 13 is raised to engage and hold the shovel arm structure in the position illustrated in FIG. 2 and upon operation opposite the arrow 27 the housing 19 is vented and the spring in the housing and gravity moves the hook 13 into inoperative position.

28 is a traction motor control valve housing and 29 an operating lever for the traction motors of the loader by means of which the loader can be driven up and down and also run in curves if desired.

When the loader according to the invention is operated in an inclined shaft as indicated by 30 in FIGS. 1a, b and 60 where it is desired to transport material from a pile of material 31 to a mine car 32 or other receiver the loader is first moved into the position 1a and the shovel motor is operated to fill the shovel and raise the shovel a little above the intermediate position illustrated in FIG. 1b. The hook 13 is then moved into operative position and this shovel lowered so it engages the hook. The operator then pulls the handle 25 in the direction of the arrow 27 to raise the hook 13. The shovel loader is then moved to the position in FIG. 1b until the loader is close to the mine car 32 or the like. In this position the operator manipulates the lever 25 or the position 26" for fulfilling the

throwing stroke so that the shovel operating motor 6 moves the shovel to discharge position, as illustrated in chain dotted lines in FIG. 1b, thereby emptying its contents into the mine car 32 or the like. Then the operator returns the shovel and loader to the position in FIG. 1a for a new shovel load by moving lever 25 as indicated by 26'. It is obvious that upon movement of the loader from the position in FIG. 1a to the position in FIG. 1b the shovel motor is not relied upon for keeping the shovel in the intermediate position illustrated in full lines in FIG. 1b with a full load of material in the shovel.

I claim:

1. In a shovel loader, a transportable substructure, a shovel movable on said substructure from a low digging position to an elevated discharge position, an arm structure arranged for carrying said shovel, a pressure fluid control valve on the substructure, an operating handle for said pressure fluid control valve on the substructure, a pressure fluid operable catching means on the substructure, a catch-engaging member on said arm structure, a pressure fluid operable power actuator arranged on the substructure for moving said catching means from an inoperative position to an operative position in which it catches and holds said catch-engaging member and the arm structure in an intermediate position between said digging and said discharge position, the arm structure being a rocker arm structure movable on rails on the substructure, and the catch-engaging member being a transverse bar carried by said rocker arm structure, the catching means comprising a hook pivotally mounted on the substructure and power swingable from an inoperative low position in which the bar may pass the hook in a direction toward discharge position but is arrested in an intermediate position upon movement in a direction from discharge position and held against swinging toward digging position in said intermediate position.

2. In a shovel loader, a transportable substructure, a shovel movable on said substructure from a low digging position to an elevated discharge position, an arm structure arranged for carrying said shovel, a pressure fluid control valve on the substructure, an operating handle for

said pressure fluid control valve on the substructure, a pressure fluid operable catching means on the substructure, a catch-engaging member on said arm structure, and a pressure fluid operable power actuator arranged on the substructure for moving said catching means from an inoperative position to an operative position in which it catches and holds said catch-engaging member and the arm structure in an intermediate position between said digging and said discharge position.

- 10 3. A shovel loader according to claim 2, in which the arm structure is a rocker arm structure movable on rails on the substructure and the catch-engaging member is a transverse bar carried by said rocker arm structure, the catching means comprising a hook pivotally mounted on the substructure and power swingable from an inoperative low position in which the bar may pass the hook to an operative raised position in which the bar may pass the hook in a direction toward discharge position but is arrested in an intermediate position upon movement in a direction from discharge position and held against swinging toward digging position in said intermediate position.
- 15 4. A shovel loader according to claim 3, in which arresting means for said shovel is controlled by an operating member provided for controlling a shovel-operating motor.
- 20 5. A shovel loader according to claim 4, in which said member is movable from a neutral position in two opposite directions for raising or lowering the shovel respectively, and in two other opposite directions for bringing the arresting means into operative and inoperative positions
- 25 30 respectively.
